UNITED STATES PATENT OFFICE

STEPHEN S. GRADY, OF MAGNOLIA, NORTH CAROLINA, ASSIGNOR TO FUSOID ELECTRIC
CO., INC., A CORPORATION OF NEW YORK

CIRCUIT BREAKER

Application filed August 31, 1928. Serial No. 303,189.

This invention relates to circuit breakers in general and more especially to circuit breakers embracing an electric switch.

Among the objects of the present invention it is aimed to provide an improved construction of a switch controlled circuit breaker in which the switch can be operated manually to break the switch and on the other hand the switch automatically operated to break the circuit as a result of an overload.

10 More specifically the present invention
aims to provide an improved switch con-
trolled circuit breaker equipped with ther-
15 mistic means for automatically operating
the switch to break the circuit in case of a
light or gradually increasing overload and
equipped with electro magnetic means where-
20 by the switch can be automatically oper-
ated to break the circuit in case of a sudden
or heavy overload.

More particularly the present invention further aims to provide a circuit breaker for use in residences and the like associated with a lighting system or the like whereby after an overload has caused the circuit breaker to break the circuit, the same can readily be reset by the average layman or unskilled attendant, without the use of tools or the like.

30 These and other features, capabilities, and advantages of the invention will appear from the subjoined detail description of one specific embodiment of the present invention illustrated in the accompanying drawings in which

Figure 1 is a plan view of a junction box partly broken away, equipped with a plurality of the circuit breakers constituting the present invention;

40 Fig. 2 is an enlarged section on the line 2-2 of Fig. 1;

Fig. 3 is an enlarged plan view of a single circuit breaker with a part of the housing removed;

45 Fig. 4 is a longitudinal section of a single circuit breaker illustrating the position of the several parts when the circuit has been broken and the unit has been removed from the junction box;

50 Fig. 5 is a similar longitudinal section of

an individual circuit breaker after the same has been reset in position to make a circuit;

Fig. 6 is an enlarged detached side elevation of the latch member forming a part of the circuit breaker;

Fig. 7 is a transverse section on the line 7-7 of Fig. 4;

Fig. 8 is a transverse section on the line 8-8 of Fig. 5; and

Fig. 9 is a fragmental section on the line 60-9-9 of section 7.

In the present embodiment there is pro-

In the present embodiment there is provided a supporting block 1 preferably composed of insulated substance such as porcelain or fiber which is preferably provided with a recess 2 at one end of the block 1 and a recess 3 in alignment with said recess 2 at the other end of the block. The recesses 2 and 3 constitute a pair for each set of connections or circuit breakers. If, as

indicated in Fig. 1, the block 1 is provided with three circuit breakers there will necessarily be three pairs of recesses 2, 3. In the recess 2 there is secured a metal outer clip 4 having an opening in its lip portion 5 to receive the screw 6 and a flexible jaw member at its inner end. In the recess 3 there is secured a similar outer clip 7 having an opening formed through its lip portion 8

to receive the screw 9, which clip 7 is also provided with a flexible jaw member 10 at its inner end. The screw 6 in the present instance is used to connect the terminal 11 of the conductor 12 through the lip portion 5, such screw 6 having its head portion rest- 85

ing against the terminal 11, and extending through the lip portion 5 and porcelain member 1 and terminating in the recess 13 where it receives the nut 14. Similarly the screw 9 extends through the terminal 15 of the conductor 16 which is separated from

the conductor 12 by means of the circuit breaker to be described, the screw 9 extending through such terminal 15 and then

through the lip portion 8 into the porcelain portion 1 and terminating in the recess 17 where it receives the nut 18. When the conductors 12 and 16 are extended through conduits as illustrated in the present instance, 95

the conduits for the conductors 12 and 16 100

are preferably connected to the junction box in the manner to be described.

The conduit 19 of the conductor 12 is screw-threaded at its end to receive the collars 20 and 21 which are screw-threadedly connected to the conduit 19 to clamp between them the edges of the wall 22 of the junction box surrounding the recess 23. Similarly the conduit 24 of the conductor 16 is screw-threadedly connected at its inner end to receive the collars 25 and 26 which clamp between them the edges of the wall 27 of the junction box surrounding the opening 28 through which the conduit 24 extends into the junction box. The junction box is designated generally by the reference character 29. Preferably the porcelain block 1 is disposed against the inner wall 30 of the junction box and is provided with screws 31 and 32 which extend through the block and wall 30 of the junction box to project outwardly into the supporting wall or member not shown. The junction box 29 is provided in the usual way with a cover 33, which in the present instance is shown as merely frictionally secured to the junction box 29. The junction box 29 and porcelain block 1 as aforesaid, may be equipped to receive a plurality of circuit breakers to, in turn, separate a plurality of pairs of conductors. In the present instance, Fig. 1, there are illustrated three pairs of conductors to wit, the pair 12, 13; the pair 12^b, 13^b, and the pair 12^b, 16^b. Since the circuit breakers for each pair of conductors are substantially identical, the circuit breaker for the conductor 12^b, 13^b alone will be described in detail.

The circuit breakers each consist essentially of an insulated body portion 34 preferably composed of porcelain or fiber. This body portion 34 is provided at one end with a supporting member 35 on which a metal member 36 is mounted which is preferably provided with two wing members 37 and 38, between which and in contact with such wing members 37 and 38 there is pivotally connected the end 39 of the main switch knife 40, the pivot pin 41 extending through the wing members 37 and 38 and the end 39 of the switch knife 40. The metal member 36 is secured to the supporting portion 35 of the insulated body member 34 by means of the screw 42. The main body portion of the switch knife 40 is disposed to operate in the main chamber 43 of the insulated body member 34 and has secured thereto a lever 44 composed of an insulated material such as porcelain or fiber. Such lever 44 in the present instance is secured to the extension 45 of the switch blade 40, is provided with a recess at 46 and has an extended arm 47 extending over and beyond the edge of the switch blade 40. The lever 44 is provided with two projections 48 and

49 hereinafter to be described more in detail.

For normally exercising a pressure on the lever 44 and in turn on the switch blade 40 into circuit breaking position, there is provided a spring 50 the ends of which are preferably supported on the upwardly extending edge 51 of the member 35. This spring 50 then curves around the pivot pin 41 with the U-shaped portion 52 thereof engaging the lever 44 in the recess 46 adjacent to the projection 49. In Fig. 4, the lever 44 and switch blade 40 are shown depressed into circuit breaking position by the spring 50. In Fig. 5, the lever 44 and switch blade 40 are shown raised in opposition to the spring 50 being disposed in circuit making position and anchored in such position by the latch member 54. The latch member 54 as particularly shown in Figs. 6, 7, and 8, consists of an arm member 55 having an elongated finger 56, a spur 57 spaced from said finger 56 and a flat arm 58 disposed at right angles to the finger 56 and provided with a recess 59 to form the shoulder 60. The arm 55 has pivotally connected thereto at 61 the flapper 62 which is provided with a tail-piece 63. Between the pivot pin 61 and the arm 58 the arm 55 is provided with an opening 64. The latch 54 is floatingly mounted in the chamber 43, having the free end of the spring 65 extending through the opening 64, which spring 65 is secured between the metal member 36 and the supporting portion 35 and exercises a tension on the latch member 54 in the same direction as the tension of the spring 50. The insulated body member 34 is provided with an opening 66. Preferably on the inside of the body portion 34 and disposed adjacent to such opening 66, there is provided a supporting plate 67 provided with an opening 68, see particularly Fig. 9. The plate 67 as shown in Fig. 9, is provided with a lip 69. The plate 67 is also provided with a recess 70 extending from the opening 68 and an opposing recess 71 to receive the free ends 72, 73, and 74 of the U-shaped member 75. The arm 58 is adapted to extend through the opening 66 and into engagement with the lower inclined end 76 of the U-shaped member 75. In the operation of the device, the finger 56 extends into the recess 92 of the blade 40, the spur 57 extends into the orifice 77 of the blade 40 to engage the lower face 78 of the blade 40 in the orifice 77 to maintain the blade 40 and lever 44 in circuit making position. The latch member 54 will be maintained in such raised position by the engagement of its shoulder 60 with the lip 69 of the plate 67, as shown in Figs. 7 and 8. A flat spring 79 is secured to the insulated body member 34 to exercise a tension on the arm 58 of the latch member 54 whereby the spur 57

will be caused to be depressed into the orifice 77 of the blade 40 and against the shoulder when the latch member 54 is permitted to extend outwardly after the circuit is broken into the position illustrated in Fig. 7 in which position, the spur 57 will be ready to engage the face 78 to raise the blade 40 when the U-shaped member 75 is pressed inwardly thereby engaging the latch member 54 and pressing it inwardly. After a circuit is broken, and when the circuit breaker thereof is to be reset, it is merely necessary to remove the circuit breaker, engage the same so that the U-shaped member 75 is pressed against an opposing surface until the latch member 54 has been raised sufficiently to permit its shoulder 60 to engage the lip 69, when the circuit breaker will be reset and be in position again to make a circuit after the circuit breaker is returned into engagement with the clips 4 and 7. When the U-shaped member 75 is so being pressed inwardly, the inclined end 76 will cooperate with the end of the latch member 54 to urge the same against the lip 69, see Fig. 9, until the lip 69 registers with the notch 59 whereupon the latch member 54 will snap into position where its shoulder 60 will engage the lip 69.

30 The insulated body portion is provided with two inner metal clips, the clip 79 and the clip 80. The inner clip 79 is adapted to cooperate with the clip 4 and engage the same, and the clip 80, is adapted to be 35 clamped into position by the clip 7. The inner clip 79, as particularly illustrated in Fig. 2, is provided with two clamping jaw members 81 and 82 adapted to receive the free end of the blade 40 in circuit making position, as illustrated in Fig. 5, and to receive the free end of the lever 44 in the circuit breaking position, as shown in Fig. 4.

40 The inner clip 80 is electrically connected by means of the conductor 83 of the electro-magnet 84 which electrical conductor 83 then extends over to the free end 85 of the laminated U-shaped thermostat 86, the other end of the U-shaped thermostat 86 being connected to the free end of the arm 87 45 extending from the metal wing 38. The intermediate end of the thermostat 86 is provided with an insulated abutment piece 88, which see Figs. 3 and 8 is adapted to be disposed opposite to the finger 56 in circuit making position.

50 From the foregoing it will be seen that in circuit making position the current will pass from the conductor 12 through the outer clip 4, inner clip 79, blade 40, wing 55 38, arm 87, thermostat 86, conductor 83, inner clip 80, and outer clip 7 to the conductor 16.

55 After the circuit breaker is in position to make circuit, then, in case of a light over-load or of a gradually increasing overload,

the thermostat 86 will gradually heat up and warp, pressing the abutment 88 into engagement with the finger 56. As soon as the abutment 88 has sufficiently pressed the finger 56 to cause the spur 57 to clear the surface 78 of the blade 40, the spring 50 will be free to snap the arm 44 and blade 40 into the chamber 43 thereby causing the blade 40 to clear the jaws 81 and 82 and cause the insulated arm 44 to engage such jaws 81 and 82 when the circuit will be broken.

60 On the other hand, in case of a sudden overload or heavy overload, the current will cause the magnet to attract the flapper 62 whereupon it will cause the tail-piece 63 to press against the blade 40 to pry the latch member 54 away from the blade 40 until the spur 57 of the latch member 54 clears the surface 78 of the blade 40, when, again the spring 50 will be free to snap the arm 44 and blade 40 into the chamber 43 whereupon the blade 40 will clear the jaws 81 and 82 to break the circuit.

65 When the arm 44 and blade 40 are snapped into position to break the circuit, the U-shaped member 75 will still rest against the block 1, the light spring 65 not being strong enough to press the latch member 54 and U-shaped member 75 outward against the block 1. However, as soon as the circuit breaker has been removed from engagement with the outer clips 4 and 7 of the junction box, the spring 65 will be free so to press the latch member 54 and U-shaped member 75 outward into position where the circuit breaker is ready to be reset by merely exercising pressure on the U-shaped member 75 until, as aforesaid, the latch member 54 has been pressed inwardly sufficiently to have its shoulder 60 again engage the lip 69. During such inward movement of the latch member 54, as aforesaid, the spring 79 exercising outward tension on the arm 55 of the latch member 54 will cause the spur 57 of the latch member 54 to engage the surface 78 of the blade 40 so that the blade 40 and arm 44 will be reset against the tension of the spring 50 simultaneously with the resetting of the latch member 54.

70 75 The circuit breaker is also provided with a cover member 89 which is provided with two openings 90 and 91 to register with the projections 48 and 49 respectively of the arm 44. When the circuit breaker is in circuit making position, the outer surface of the projections 48 and 49 will be substantially flush with the outer surface of the cover 89 and will be clearly seen as for instance in the left hand circuit breaker of the two shown in Fig. 1. On the other hand, when the circuit is broken and the arm 44 is swung inwardly away from the cover member 89, such projections will be depressed, and not be readily visible, see for 80 85 90 95 100 105 110 115 120 125 130

instance, the second from the left of the two circuit breakers shown in Fig. 1. By this means, when insulating a junction box, to find a circuit breaker which is in circuit breaking position, the same can be readily detected by removing the outer cover 38 and without removing the inner cover 39 of each individual circuit breaker.

From the foregoing it will be seen that the spring 72 serves two purposes. When in the latch member 54 is in circuit breaking position and pressure from the body member 24, the spring 72 will urge the spur 57 into the notch 57 so that the latch member 54 will automatically be positioned to return the blade 51 from circuit making position when it is pressed inward. On the other hand, the spring 72 serves as a fulcrum for the latch member 54 in circuit making position, around which fulcrum the latch member 54 will be rocked when the shank 18 engages the finger 50 in turn to cause the shoulder 36 to clear the lip 38 to effect the latch member 54 as soon as the circuit breaker is removed from the junction box 29.

It is obvious that various changes and modifications may be made to the details of construction without departing from the general spirit of the invention as set forth in the appended claims.

I claim:

1. A circuit breaker comprising a pair of terminals, a pair of contact jaws operatively associated with one of said terminals, a switch blade pivotally connected at one end and adapted to engage said jaws in circuit making position, an insulated lever operatively associated with said switch blade, a spring operatively connected to actuate said blade into circuit breaking position and to interpose said insulated lever between said contact jaws, a latch for anchoring said blade in circuit making position against the tension of said spring, and a thermostatic operating member operatively connecting the other end of said blade with the other terminal, said thermostatic operating member being operative to trip said latch in case of a light overload to permit said spring to snap said blade into circuit breaking position.

2. A circuit breaker comprising a pair of terminals, a pair of contact jaws operatively connected to one of said terminals, a switch blade pivotally connected at one end and adapted to engage said contact jaws in circuit making position, an insulated lever operatively associated with said switch blade, a spring operatively connected to actuate said blade into circuit breaking position and to interpose said insulated lever between said contact jaws, a latch for anchoring said blade in circuit making position against the tension of said spring, a thermostatic op-

erating member operatively connecting the other end of said blade with the other terminal, and a thermostatic operating member operatively connecting said other end of said blade with said other terminal, said thermostatic operating member being operative to trip said latch in case of a light overload to permit said spring to snap said blade into circuit breaking position, and said thermostatic operating member being operative to trip said latch in case of a overload.

3. A circuit breaker comprising a pair of terminals, a stationary contact operatively connected to one of said terminals, a pivotally connected insulated arm, a projection formed on said arm, a switch blade secured to said arm and engaged in abutment with said contact in circuit making position, a spring operatively connected to move said blade into circuit breaking position, a latch for anchoring said blade in circuit making position against the tension of said spring, overload detecting means operatively connecting the other end of said blade with the other terminal, said detecting means being operative to trip said latch in case of an overload to permit said spring to snap said blade into circuit breaking position, and a cover for said circuit breaker having an orifice disposed to receive said projection when said arm is in circuit making position, said projection being positioned on said arm to re-cede from said orifice when actuated into circuit breaking position to facilitate inspecting the circuit breaker without removing said cover.

4. A circuit breaker comprising a pair of terminals, a pair of contact jaws operatively connected to one of said terminals, a switch blade pivotally connected at one end and adapted to engage said contact jaws in circuit making position, an insulated lever operatively associated with said switch blade, a spring operatively connected to actuate said blade into circuit breaking position and to interpose said insulated lever between said contact jaws, a latch for anchoring said blade in circuit making position against the tension of said spring, and overload detecting means operatively connecting the other end of said blade with the other terminal, said detecting means being operative to trip said latch in case of an overload to permit said spring to snap said blade into circuit breaking position.

5. A circuit breaker comprising a pair of terminals, a stationary contact operatively connected with one of said terminals, a switch blade pivotally connected at one end and adapted to engage said contact in circuit making position, a spring operatively connected to actuate said blade into circuit breaking position, a latch for anchoring said blade in circuit making position against the

5 tension of said spring, overload detecting means operatively connecting the other end of said blade with the other terminal, said detecting means being operative to trip said latch in case of an overload to permit said spring to snap said blade into circuit breaking position, an insulated body member associated with said circuit breaker, there being an opening in said body member, a second 10 spring for causing said latch to protrude from said opening after a circuit has been broken, and means for operatively connecting said latch when in protruded position with said blade so that the return of said latch into said housing into latch anchoring position will in turn return said blade into circuit making position.

6. A circuit breaker comprising a pair of terminals, a stationary contact operatively associated with one of said terminals, a switch blade pivotally connected at one end and adapted to engage said contact in circuit making position, a spring operatively connected to actuate said blade into circuit 20 breaking position, a latch for anchoring said blade in circuit making position against the tension of said spring, overload detecting means operatively connecting the other end of said blade with the other terminal, said detecting means being operative to trip said latch in case of an overload to permit said spring to snap said blade into circuit breaking position, an insulated body member associated with said circuit breaker, there being an opening in said body member, a second spring for causing said latch to protrude from said opening after a circuit has been broken, and a third spring 25 for urging said latch when in protruded position into engagement with said blade so that the return of said latch into said housing into latch anchoring position will in turn return said blade into circuit making position, said second spring, third spring, and the edges of said opening cooperating with one another to guide said floatable latch in its several operative positions.

STEPHEN S. GRADY.

95

associated with one of said terminals, a switch blade pivotally connected at one end and adapted to engage said contact in circuit making position, a spring operatively connected to actuate said blade into circuit breaking position, a floatable latch for anchoring said blade in circuit breaking position against the tension of said spring, overload detecting means operatively connecting the other end of said blade with the other terminal, said detecting means being operative to trip said latch in case of an overload to permit said spring to snap said blade into circuit breaking position, and insulated body member associated with said circuit breaker, there being an opening in said body member, a second spring for causing said latch to protrude from said opening after a circuit has been broken, and a third spring for urging said latch when in protruded position into engagement with said blade so that the return of said latch into said housing into latch anchoring position will in turn return said blade into circuit making position, said second spring, third spring, and the edges of said opening cooperating with one another to guide said floatable latch in its several operative positions.
